UNITED STATES PATENT OFFICE.

LEWIS KULCSAR, OF PUNXSUTAWNEY, PENNSYLVANIA.

AIRPLANE.

1,271,480.

Specification of Letters Patent.

Patented July 2, 1918.

Application filed November 7, 1917. Serial No. 200,789.

To all whom it may concern:

Be it known that I, LEWIS KULCSAR, a citizen of the United States, residing at Punxsutawney, in the county of Jefferson 5 and State of Pennsylvania, have invented new and useful Improvements in Airplanes, of which the following is a specification.

This invention relates to airplanes, the object in view being to produce a novel form 10 of airplane which will closely resemble a butterfly and which will be nearly or quite invisible at a comparatively low altitude thus particularly adapting the same for military and naval purposes.

15 A further object of the invention is to simplify and improve the means for maintaining the longitudinal and lateral stability of the machine while retaining the ordinary stabilizing means such as the vertical and 20 horizontal rudders, additional stabilizing means, hereinafter referred to as trailing wings, being also useful for emergency purposes, when, for any reason the vertical rudder or horizontal rudder should both become 25 inoperative.

With the above and other objects in view, the invention consists in the novel construction, combination and arrangement of parts, herein described, illustrated and claimed.

30 In the accompanying drawings:—

Figure 1 is a plan view of the improved airplane.

Fig. 2 is a side elevation thereof.

Fig. 3 is a front elevation of the same.

35 Fig. 4 is a cross section through the body or fuselage.

Fig. 5 is a cross section through one of the leading wings.

40 Fig. 6 is a cross section through one of the trailing wings.

Referring to the drawings A designates the body or fuselage of the airplane, B the leading wings, C the trailing wings, D the vertical rudder, H the horizontal rudder, I the engine, located at the front end of the fuselage, and K a tractor propeller fast on the engine shaft.

45 In carrying out the invention, the fuselage A is composed of longitudinal and transverse frame members 1 and 2 respectively, said members being preferably composed of light metal strips of angle iron and T-iron construction in cross section. In the substantially rectangular spaces between the 50 frame members 1 and 2, blocks or sheets 3

of mica or other suitable material are permanently fastened in any suitable way.

Each of the leading wings B is likewise composed of a skeleton frame work or frame members 4 and 5 extending longitudinally and transversely thereof, certain of said frame members being of angle iron formation and others of T-iron formation and having blocks or sheets 6 of mica or other translucent or semitranslucent material placed within the spaces formed thereby and secured by any suitable means.

60 In like manner the trailing wings C are formed of frame members 7 and 8 of a formation similar to those above described, the spaces formed by the frame members 7 and 8 being filled with blocks or sheets 9 of mica or like material.

65 The leading wings B progressively increase in width or chord from the body toward the outer ends thereof, the trailing edges 10 of the leading wings B having a rearward rake and gradually diverging from the leading edges 10 thereof as clearly shown in the plan view Fig. 1. The leading edges 70 12 of the trailing wings C are substantially parallel to the trailing edges 10 of the leading wings B but arranged in a lower plane so as not to be affected by or to affect the turbulent air leaving the trailing edges of 75 the leading wings. The trailing wings are triangular in shape, having rearwardly diverging inner edges 13 and rearwardly converging outer edges 14. This gives to the machine as a whole a close resemblance to 80 a butterfly. The leading edges 12 of the trailing wings C are connected to rock shafts 85 15 which extend the full length thereof and project at their rear ends into the body or fuselage A where they are provided with operating arms or levers 16 by means of which the aviator is adapted to vary the angle of incidence of the trailing wings. The vertical and horizontal rudders D and H are constructed in the same manner as 90 the leading and trailing wings, of a skeleton frame work and blocks or sheets of mica, in fact this feature of construction is carried out throughout the whole machine so as 95 to render the same invisible or substantially 100 so at a comparatively low altitude. The landing gear comprises a pair of floats or pontoons 17 having planing surfaces 18 and equipped with front and rear wheels or rollers 19 and 20 thus adapting the machine to 105 110

land upon or rise in flight from either the land or water. Suitable stay wires 21 connect the leading wings B with the body or fuselage and guy wires 22 serve to brace 5 the rock shafts 15 in relation to the body or fuselage.

From the foregoing description taken in connection with the accompanying drawings it will be understood that by simultaneously 10 elevating the trailing portions of the trailing wings, the air plane will be directed upwardly and conversely by depressing the trailing portions of the trailing wings, the machine will be directed downwardly. By 15 raising one of the trailing wings and depressing the other trailing wing, any desired bank may be imparted to the machine. Should the horizontal rudder or the vertical rudder or both become disabled for any reason, by means of the trailing wings C, the machine may be caused to ascend or descend 20 or to turn to the right or to the left by the proper manipulation of the trailing means

for said trailing wings. This imparts to the machine a very great factor of safety.

I claim:—

1. In airplane construction, a fuselage, wings, and trailing surfaces, each of said parts embodying a skeleton frame work consisting of longitudinal and transverse frame 30 members certain of which are of T-formation in cross section and other of which are of angle iron formation in cross section, and sections of substantially transparent material filling the spaces bounded by said frame 35 members between the points of intersection thereof.

2. In airplane construction, a frame comprising a marginal frame member of angle iron formation, longitudinal and transverse 40 frame members of T-formation, and sections of substantially transparent material filling the spaces bounded by said frame members between the points of intersection thereof.

In testimony whereof I affix my signature. 45
LEWIS KULCSAR.
